SLIP

Albert A. Horwitch, Chicago, Ill.

Application October 16, 1941, Serial No. 415,322

1 Claim. (Cl. 2—73)

This invention relates primarily to a slip, that is to say, to that type of woman's undergarment which is commonly known as a slip.

Heretofore in the art it has been common practice among manufacturers of women's slips to make the same of generally either two or four gores or panels, and in relatively few cases perhaps of six gores. There are, however, a number of objectionable features to such prior art slips and among these is the fact that such prior art slips when worn or in use tend to sag along the seam portions thereof where the gores are joined together due, in part, to the fact that in making such prior art slips it is necessary to cut the material of which the gores are made largely on the bias to form the gores in such a manner that they are substantially wider at the bottom than they are at the top, as is necessary in order to make a slip since slips are customarily wider at the bottom and throughout the skirt portion thereof than they are at the top and throughout the waist or bodice portion thereof.

The necessity for cutting the gores on a considerable bias, in making the prior art slips, causes a number of undesirable effects or results in the resulting slip, when the slip is worn, and among these are the fact that such slips, because of the pronounced bias cut of the gores, tend to stretch both laterally or transversely and lengthwise of the garment, thereby causing wrinkling and bulging of the slip and sagging of the same, especially along the seams thereof. This imparts a generally unattractive appearance to the overlying or outer garment of the wearer and since such a slip tends to sag along the seams the slip will hang unevenly and the bottom hem portion thereof will sag downwardly, along the seams, below the bottom of the wearer's outer garment, thereby causing the generally unattractive appearance which is referred to above.

Moreover, it is impossible to make a slip, composed of only two, or four, or six gores, having a relatively narrow waist portion and a relatively wide or flaring skirt portion, as is possible and as is accomplished in making the new slip which forms the subject matter of the present invention, since if a slip composed of only two, or four, or six gores is so designed it will possess the above mentioned and other undesirable features.

I have found, however, that the foregoing and other difficulties which are experienced in the use of the prior art slips are overcome and eliminated in the use of the new slip which forms the subject matter of the present invention and

which embodies an even number of gores not less than eight.

I have also found that in use the new slip is free from any tendency to sag or wrinkle along the seam portions thereof and has, when worn, a neat, attractive appearance which is enhanced by the contrast between the relatively narrow waist line and bodice portion of the new slip and the outwardly flaring bottom portion thereof.

Moreover, since the new slip is composed of not less than eight gores, the gores may be and are formed by cutting them with only a relatively slight bias as compared to the bias cut which is required when a slip is made of only two, or four or six gores, and hence the new slip is free of that tendency to stretch and sag, due to the pronounced bias cut of the gores, as is inherent in the prior art slips, as pointed out above.

Accordingly, an object of the present invention is to afford a new slip which in use overcomes the above mentioned and other difficulties experienced in the use of the prior art slips and which has the foregoing and other novel and advantageous features and advantages.

Other and further objects of the present invention will be apparent from the following description and claims and will be understood by reference to the accompanying drawing which, by way of illustration, shows a preferred embodiment and the principles thereof and what I now consider to be the best mode in which I have contemplated applying those principles. Other embodiments of the invention embodying the same or equivalent principles may be used and changes may be made as desired by those skilled in the art without departing from the present invention and the purview of the appended claim.

In the drawing:

Fig. 1 is a front elevational view of a slip embodying the present invention;

Fig. 2 is a rear elevational view of the same; and

Fig. 3 is a transverse sectional plan view there-

of on line 3—3 in Fig. 1.

A slip embodying the invention is illustrated in the drawing, wherein it is generally indicated at 10, and comprises an upper or bodice portion 11 and a lower or skirt portion 12. As shown, lower or skirt portion 12 of the new slip 10 consists of eight gores 13 which are joined together, by suitable stitching, along seam lines 14 which extend from the bottom hem 16 of the slip to the seam 15 at which the bodice portion 11 and the skirt portion 12 of the slip are joined together.

It is to be understood, however, that the new slip is not limited to the particular design of the bodice which is shown in the drawing since, if desired, bodices of other designs may be employed or, if desired, the gores 13 could extend throughout the entire length of the slip, that is to say, from the top to the bottom thereof, although in its preferred form, the gores 13 extend only up to the bottom or lower seam of the bodice.

It will be noted, by a careful consideration of Figs. 1 and 2 of the drawing, that the skirt portion 12 of the new slip tapers considerably from the upper end thereof, where it is relatively narrow, to the bottom thereof where it is relatively wide so that the new slip has the desired and fashionable narrow waist but is relatively wide and flares outwardly at the bottom thereof.

It will be noted, however, that by reason of the fact that the skirt portion of the new slip 10, as shown, is composed of eight gores, each gore 13 is cut only slightly on the bias of the goods, compared to the extent or degree of bias cut which is required when employing only two, or four or six gores, and since, as is well understood by persons skilled in the art, as the bias cut is increased the tendency of the material to stretch and sag is increased correspondingly, it will be seen that in the new slip the desired difference in width between the top and bottom of the skirt portion thereof is secured while, at the same time, the tendency of the slip to stretch and sag, particularly along the seams thereof is eliminated, or, at least, greatly reduced or minimized. This is due, to a large extent, to the fact that since the total and desired difference between the top and bottom portions of the skirt portion of the new slip is divided up equally between eight gores, rather than between only two, or four or six gores, as in the prior art slips, the result is that the amount or degree of bias cut in each gore is materially reduced while at the same time there is obtained in the new slip the desired relatively narrow waist and marked outward flare in the skirt portion thereof.

It will be apparent to persons skilled in the art, from the foregoing description, considered in the light of and in conjunction with the accompanying drawing, that the present invention and the new slip which forms the subject matter thereof overcome the above mentioned and other difficulties which are inherent in the use of the prior art slips, and that the present invention thus accomplishes the above mentioned and other objects of the invention and provides a slip which is neat and attractive in appearance and has the desired relatively narrow waist portion and outwardly flaring skirt or bottom portion while, at the same time, being free from the tendency of prior art slips, composed of only

two, or four or six gores, to stretch, wrinkle and sag, especially along the seams thereby causing the resulting undesirable appearance, when worn, thereof, as explained hereinbefore.

While the new slip has been illustrated in the drawing as being composed of eight gores, and this is the preferred number of the same, it will be understood that an even number of gores greater than eight such, for example, as ten gores may also be employed within the purview of, and without departing from the scope of, the present invention.

It will also be understood that while the present invention is primarily applicable to women's slips, it may also be applied to other articles or types of women's underwear, or lingerie, such as gowns and the like, without departing from the purview or scope of the present invention.

I claim:

- 20 A woman's slip including a skirt portion comprising eight gores or panels of substantially the same size joined together at the side edges thereof by stitching along seam lines, each of the said gores being tapered slightly, in plan, so that each of the said gores is somewhat wider at the bottom than it is at the top thereof whereby due to the relatively large number of said gores the said skirt portion of the said slip is substantially wider at the bottom than it is in the upper and waist portion thereof and a pronounced outward flare is imparted to the said skirt portion of the said slip, each of said gores or panels having both the woof and the warp threads thereof extending at an angle relative to its own longitudinal center line, whereby said slip is substantially free from tendency to wrinkle or to sag along the seam portions thereof or elsewhere in the said skirt portion of the said slip, said slip including a bodice portion joined at its lower edge to the upper edge of the said skirt portion of the said slip by stitching along a seam line, the front of the said skirt portion of the said slip embodying two centrally arranged gores or panels each having the upper edge thereof joined to the lower edge of the front of the said bodice portion of said slip and the upper edge of each of said centrally arranged front gores being curved so that the highest point in the said upper edge of each of the said two said centrally arranged gores in 40 the front of the said skirt portion of said slip is disposed below one of the busts of the wearer of the slip, when the said slip is in use, and the upper edge portions of the two said centrally arranged front gores are joined to the said bodice portion of the said slip along a curved line extending concavely downwardly between the said two highest points.
